UNITED STATES PATENT OFFICE.

AMIAH J. KERN, OF BELLEVUE, OHIO.

CUTTING DEVICE.

SPECIFICATION forming part of Letters Patent No. 593,477, dated November 9, 1897.

Application filed May 19, 1897. Serial No. 637,218. (No model.)

To all whom it may concern:

Be it known that I, AMIAH J. KERN, a citizen of the United States, residing at Bellevue, in the county of Huron and State of Ohio, have invented certain new and useful Improvements in Cutting Devices; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to improvements in devices for handling and cutting butter, lard, tallow, &c.; and it consists, essentially, of a rotatable adjustable knife or cutter, a holder for said knife or cutter, and means for holding said knife or cutter in position for use, and a carrier or other receptacle for delivering the material to be cut to the knife or cutter.

The invention further consists in the novel construction and arrangement of the several parts of the device with reference to each other, as illustrated in the drawings, described in the specification, and more particularly pointed out in the claim hereunto appended.

In the drawings, Figure 1 is an elevation of my improved cutter in position for use and the box or receptacle. Fig. 2 is an elevation showing the box or receptacle and the cutter swung or held out of the way when out of use. Fig. 3 is a longitudinal view, partly in section.

35 A represents a refrigerator or other storage-box, provided with a suitable door A' and having therein a sliding receptacle or carrier B for the purpose of holding and delivering the material to the knife when it is desired to cut or sever it. This carrier B has in it, running longitudinally thereof, cleats or tracks b b for the purpose of keeping the material to be operated upon in the desired position for cutting, and also for the purpose of enabling the operator to slide the material in the said carrier forward to the desired position with the greatest ease and accuracy. To the outside of this box A, on an extension or platform a, is an upright pivoted standard C, having at intervals thereon circumferential grooves c, as shown. At the top of this upright is a clip or holder C', made of spring-steel or other suitable material, and which is reinforced by a forked-shaped bracing-plate C², the whole being securely held to the said

standard by a bolt and nut or in any other suitable manner.

D is a sliding collar adjustably secured upon the standard C by means of a thumb-nut d. The collar D is provided with ears d' d', as shown.

E is a knife-bracket, bent to the shape shown. The bracket E is pivoted between the ears d' d' by bolt f or any other suitable means. This bracket is both removable from the collar and adjustable between the lugs, as is apparent. On the end of the bracket at which it is pivoted is a handle F'. At the end of the leg F² of the bracket F is secured one end of a wire knife H, as shown. In the opposite leg is an opening or channel F³, into which sets and fits a bolt G, having one portion thereof screw-threaded and provided with an adjusting-nut G', while at the opposite end thereof is an eye g, into which is secured the opposite end of the wire knife H. This screw and nut form a tension whereby the knife is set at and held to the proper degree of tautness. The grooves c c in the standard C are for the purpose of receiving the ends of the binding-screws in the collar D.

When it is desired to cut by means of this device, the material to be operated upon is run under the knife and the handle is pressed down, as is the case in a number of devices for similar purposes, and when the device is not in use the bracket can be raised and held in such position by the holder or clip C', as is evident.

By reason of the wire knife used herein the cutting of the material is made easier and there can be no loss by reason of butter or lard adhering to the knife, as is usually the case where sticky substances are cut.

Having thus described my invention, what I claim, and desire to secure by Letters Patent of the United States of America, is—

In a device of the character described the combination of a standard C, having grooves c thereon and a holder or clip C' at the top thereof, with an adjustable collar D, a bracket E pivoted thereto, and an adjustable wire knife secured in said bracket, as set forth.

In testimony whereof I affix my signature in presence of two witnesses.

AMIAH J. KERN.
